UNITED STATES PATENT OFFICE.

HARRY NAGLER, OF BROOKLYN, NEW YORK.

SHOW-CASE LOCK.

1,352,680.

Specification of Letters Patent. Patented Sept. 14, 1920.

Application filed May 27, 1920. Serial No. 384,704.

To all whom it may concern:

Be it known that I, HARRY NAGLER, a citizen of the United States, residing at Brooklyn, in the county of Kings and State of New York, have invented certain new and useful Improvements in Show-Case Locks; and I do declare the following to be a full, clear, and exact description of the invention, such as will enable others skilled in the art to which it appertains to make and use the same.

This invention relates to show case locks, and is particularly designed for use in connection with show cases having oppositely sliding glass doors.

One object of the invention is to provide a means whereby the oppositely sliding glass doors of a show case or the like may be locked in closed position without in any way reconstructing or adapting the glass doors for the attachment of the device thereto.

Another object of the invention is to provide a device of this character, the construction of which is extremely simple, strong, easy and cheap to manufacture, will be efficient and reliable in operation, and is well adapted to the purpose for which it is designed.

With these and other objects in view the invention consists of the novel features of construction, and the combination and arrangement of parts as will be hereinafter fully described and claimed.

In the accompanying drawing in which similar reference characters are used to designate like parts throughout the several views:

Figure 1 is an elevation of a portion of a show case having a device constructed in accordance with this invention applied thereto, the device being shown in locked position.

Fig. 2 is a view similar to Fig. 1 except that the device is shown in unlocked position and in the act of being removed.

Figs. 3 and 4 are horizontal sectional views taken on the planes indicated by the lines 3-3 and 4-4 of Figs. 1 and 2 respectively.

Fig. 5 is a perspective view of the device.

In the embodiment illustrated the number 1 designates a portion of the bottom of a show case, and 2 and 3 are the oppositely sliding glass doors of the show case. As

clearly shown, these doors 2 and 3 when in closed position have one of their ends in overlapping relation. The door 2 may be opened by sliding it to the right and the door 3 may be opened by sliding it to the left. As shown in Figs. 3 and 4 the doors 2 and 3 are slightly spaced from each other in a direction transverse with respect to the show case.

The present invention is in the form of a rectangular metallic plate 4, one end of which is bent upwardly to form a flange 5 while one longitudinal edge of the plate is flared upwardly to form a finger engaging socket 6. Extending laterally from one edge and one end of the flange 5 is an arm 7, from the free end of which extends a lateral finger or lug 8. The arm 7 is disposed in a plane parallel to the plate 4 and extends substantially longitudinal with respect to said plate and the lug 8 is disposed in the plane of the arm 7. Projecting downwardly from the lower side of the plate 4 is a pair of spaced apertured lugs 9.

The bottom of the show case is provided with a suitable lock 10 having a pair of hook shaped sliding bolts 11.

In Fig. 1 the device is shown in locked position, and from this it will be seen that the plate 4 rests flat upon the bottom 1 of the show case with the flange 5 bearing against the end of the door 3. The lugs 9 extend into suitable openings arranged in the bottom 1 of the show case and the hook shaped bolts 11 of the lock 10 are inserted into the opening of said lugs so that the plate 4 is locked against upward and sliding movement. The arm 7 as shown in Fig. 3 extends between the overlapped ends of the doors 2 and 3, and the lug 8 hooks around and bears against the edge of the door 2. The door 2 is thus locked against sliding movement to the right, and the door 3 is locked against sliding movement to the left. When it is desired to unlock the doors of the show case, the lock 10 is actuated by the insertion of an appropriate key in the key-hole so as to move the bolts 11 to the right and withdraw their hook-shaped ends from the apertures in the lugs 9.

When this has been done the plate 4 may be raised by engagement of the fingers with the recess or socket 6. The plate 4 must first be raised to the dot and dash line position shown in Fig. 1 so that the

lugs 9 will be disengaged from the openings in the bottom of the show case. The plate 4 may then be swung upon the arm 7 as an axis to the position indicated in full line in Fig. 2 so that the lug 8 points downwardly and becomes disengaged from the edge of the door 2. When in this position the plate 4 may be slid longitudinally so that the arm 7 and lug 8 may be withdrawn from between the doors 2 and 3. This final position is indicated by the dot and dash lines in Fig. 2. The plate is then free and may be placed away until it is again to be used. The doors 2 and 3 are then unlocked and may be opened and closed whenever desired.

From the foregoing description taken in connection with the accompanying drawings, it will be seen that the objects of the invention have been effectively carried out, as the device may be attached to a show case having glass doors without first especially adapting or reconstructing such doors for the attachment of the device thereto.

It is obvious that the device must necessarily be modified or changed in construction or in proportion to adapt it to be used in connection with all types of show cases, and such changes and modifications may be made within the scope of the appended claims.

What is claimed is:

1. The combination with a bottom and oppositely sliding doors of a show case, of a member detachably locked to the bottom of the show case and having portions abutting the ends of the doors thereof to prevent opening of said doors.

2. The combination with the bottom and oppositely sliding doors of a show case, said doors having one of their ends overlapped when in closed position, of a member detachably locked to the bottom of a show case and abutting the overlapping end of one of said doors to prevent opening of this door, said member having an extension extending between the overlapped ends of said doors and provided with means abutting the overlapped end of the other door to prevent opening of this door.

3. The combination with the bottom and oppositely sliding doors of a show case, said

doors having one of their ends overlapped when in closed position, a lock mounted in the bottom of the show case, a plate resting upon the bottom of the show case and detachably engaged by said lock, one end of said plate being upturned and abutting the overlapped end of one of said doors to prevent opening of this door, and an arm carried by the upturned end of said plate and extending between the overlapped ends of said doors and provided with means abutting the overlapped end of the other door to prevent opening of this door.

4. The combination with the bottom and oppositely sliding doors of a show case, said doors having one of their ends overlapped when in closed position, a lock mounted in the bottom of the show case, a plate resting upon the bottom of the show case and detachably engaged by said lock, one end of said plate being upturned and this upturned portion abutting the overlapped end of one of said doors to prevent opening of this door, an arm projecting laterally from the upper edge and one end of the upturned end of said plate and extending between the overlapped ends of said doors, and a lug extending laterally from the free end of said arm and abutting the overlapped end of the other door to prevent opening of this door.

5. A device of the class described comprising a plate having one end upturned, an arm extending laterally from the upturned end of said plate and provided at its free end with a laterally projecting lug, and lock bolt keepers disposed upon the lower side of said plate and depending therefrom.

6. A device of the class described comprising a plate having one end upturned, and one edge flared upwardly to form a finger engaging socket, an arm projecting longitudinally of said plate from the upper edge and one end of the upturned portion thereof, a lug projecting laterally from the free end of said arm, and lock bolt keepers disposed upon the lower side of said plate and depending therefrom.

In testimony whereof I have hereunto set my hand.

HARRY NAGLER.
